W. H. CROWLEY & A. FITZGERALD,
VACUUM STEAM HEATING SYSTEM,
APPLICATION FILED FEB. 2, 1912.

1,071,214.

Patented Aug. 26, 1913.

UNITED STATES PATENT OFFICE.

WILLIAM H. CROWLEY, OF MARINE CITY, AND AUGUSTUS FITZGERALD, OF DETROIT, MICHIGAN, ASSIGNEES TO MOREHEAD MANUFACTURING COMPANY, OF DETROIT, MICHIGAN, A CORPORATION OF MICHIGAN.

VACUUM STEAM-HEATING SYSTEM.

1,071,214.

Specification of Letters Patent. Patented Aug. 26, 1913.

Application filed February 2, 1912. Serial No. 674,930.

To all whom it may concern:

Be it known that we, WILLIAM H. CROWLEY and AUGUSTUS FITZGERALD, citizens of the United States of America, residing at 5 Marine City and Detroit, in the counties of St. Clair and Wayne, respectively, and State of Michigan, have invented certain new and useful Improvements in Vacuum Steam-Heating Systems, of which the following is 10 a specification, reference being had therein to the accompanying drawings.

The invention relates to vacuum steam heating systems and it is the object of the invention to provide automatic means for 15 maintaining the vacuum.

To this end the invention consists in the novel construction of an automatically operating device which performs the double function of the vacuum pump and the means for 20 returning the water of condensation to the boiler, as hereinafter set forth.

In the drawings, Figure 1 is a diagrammatic view of the system; Fig. 2 is a sectional elevation of the automatically operating mechanism; Fig. 3 is a horizontal section through a portion of the apparatus; 25 and Fig. 4 is a fragmentary vertical section similar to Fig. 2, showing a different adjustment of parts.

30 A is a steam generator of any suitable construction, B is the outgoing steam conduit connected with the radiator C, and D is the return conduit for the water of condensation leading to a receiver E from which it 35 is returned to the boiler.

F is an automatic device for returning the water from the tank E to the boiler and which is of the following construction:

G is a tank or receptacle which is mounted 40 upon a tilting frame comprising the conduits H and I connected with the hollow trunnions J, which latter are pivotally supported in bearings K rising from a base L. The conduit H is for the introduction of steam and is connected with the boiler by suitable connections controlled by a valve M in one of the trunnion bearings. The conduit I is connected with a channel in the opposite trunnion and the latter is connected 45 with inlet and outlet conduits N and O having check valves P and P' therein.

Q is a pivot lever fulcrumed in a standard R on the base, one end of which lever is in engagement with a bearing on the tilting

frame, while the other end is provided with 55 a counterweight S. The bearing on the frame for the lever is preferably formed by a laterally projecting pin S' on an angle fitting S² forming a part of the conduit I.

T is a lever for controlling the valve M 60 being pivotally connected to a stem of said valve and having a fulcrum link T' for connecting it to the base. The free end of this lever projects into engagement with a roller bearing T² which is preferably mounted on 65 a standard T³ engaging and rising from a bearing T⁴ on the pin S'.

U is a sprinkler conduit extending into the receptacle G and coupled by a flexible hose U' with a conduit U² forming a water 70 supply.

V is a valve controlling the conduit U² which is operated by a lever V' pivotally attached to the stem of the valve and also connected with a fulcrum link V². 75

V³ is a link pivotally connected to the lever T and depending therefrom, and V⁴ is a bearing at the end of the lever V' slidably engaging the link V³ and bearing against a stop V⁵ thereon. 80

With the construction as thus far described, in the normal position of parts the tank or receptacle G is raised by the weight S on the lever Q and normally rests upon a supporting standard W rising from the base. 85 In this position the connected levers T and V' are in such positions as to close the valve M and open the valve V. Thus water will be admitted from the conduit U² to the flexible conduit U' and from the latter to 90 the sprinkler U where it will be sprayed in the tank G and will gradually fill the latter with water. When the proper level is reached the weight of the tank will overbalance the weight S due to the fact that the 95 trunnions of the tilting frame are arranged at one side of the longitudinal axis of the tank and thus the tank is permitted to drop until it rests upon a standard W'. This operation will adjust the levers T and V' so 100 as to open the valve M and close the valve V. Upon the opening of the valve M, steam under the boiler pressure is admitted through the conduit H which rises in the tank to a point above the water level and the 105 pressure of steam on the top of the water will force it to discharge through the conduit I connected to the conduits N and O.

The check valve P prevents the water from passing to the conduit N, but the check valve P' is free to open, permitting the water to flow through the conduit O which forms the discharge connection. As soon as the tank G is emptied the weight S will again operate to tilt the frame in the reverse direction and to reverse the position of the valves M and V, closing the former and opening the latter. Thus water will again be admitted to the sprinkler U which discharges it through the steam in the tank G, causing a condensation and producing a suction or partial vacuum therein. All communication to the tank G with the exception of the conduit N, is closed, and therefore, any liquid or air which is contained in this conduit will be drawn into the receptacle.

The apparatus above described is connected in the system by coupling the conduit N with the receiving tank E for the water of condensation while the conduit O leads to the boiler. In case the return conduit D is above the boiler level the conduit O may lead directly to the boiler and the water discharged therethrough will be introduced by the combined action of the boiler steam pressure and gravity. If however, the return conduit D is upon a lower level than the boiler as indicated in the diagram, the water cannot be returned directly to the boiler as that would necessitate overcoming the steam pressure therein and also the elevation of the water to the proper level. This obviously could not be accomplished by boiler pressure alone, and therefore, a second apparatus F' similar to F and arranged above the boiler, is used for receiving the discharge from the lower tank and alternately forcing the same into the boiler. The construction of the apparatus F' may be just the same as F but the sprinkler U for causing the condensation of the steam is not essential, it being merely necessary to vent the receptacle during the filling operation, the water being raised by a steam pressure in the lower apparatus. To simplify the construction we use the same apparatus for F and F' but provide an adjustment by which a sprinkler may be thrown out of operation and the vent provided of the following construction:

X is a three-way valve arranged in the conduit U² which in one position of adjustment couples said conduit with the flexible conduit U' and in another position couples the conduit U' with the trunnion bearing K connecting with the conduit H. Y is a second three-way valve located in the conduit U² beyond the valve V and which in one position of adjustment couples said conduit with the flexible conduit U' and in another position cuts off this communication and opens a vent to the conduit U². Thus by adjusting the valves X and Y into one position the apparatus will operate as previously

described while in their other position of adjustment the tank G is vented during the filling operation.

In the operation of the heating system the automatic mechanism will act as a vacuum pump for removing both the water of condensation and the air collecting in the radiator pipes. At the same time the construction is one requiring no motive power other than the steam and having neither piston nor other parts liable to get out of order or become leaky.

What we claim as our invention is:

1. In an automatic trap, a receptacle having a check controlled inlet for water of condensation, and a check controlled discharge, a valve controlled water sprinkler within said receptacle, a valve controlled steam inlet through the upper portion of said receptacle, a weighted lever operated by the accumulation of water within said receptacle, a link having connection with valve operating mechanism for closing said sprinkler valve and opening said steam valve and for reversing said valves upon the discharge of water from the receptacle.

2. In an automatic trap, a receptacle having a check controlled inlet for water of condensation and a check controlled outlet, a water sprinkler arranged in the upper portion of said receptacle, a controlling valve therefor, a valve controlled steam inlet to the upper portion of said receptacle, a weighted lever operated by the accumulation of water within said receptacle, a link having connection with said weighted lever and operated thereby, for closing said sprinkler valve and opening said steam inlet valve and to reverse said valves upon the discharge of water from the receptacle.

3. In an automatic trap, the combination of a rockable receptacle having a check controlled inlet for water of condensation, and a check controlled discharge, a sprinkler arranged in the upper portion of said receptacle, a valve controlling the same, a valve controlled steam inlet to the upper portion of said receptacle, a weighted lever operated by the accumulation of water within said receptacle, a seat formed in one end of said levers, a link, one end of which is adapted to be received by said seat and having its remaining end connected with valve operating mechanism, to close said sprinkler valve and open said steam valve, whereby the accumulated water is ejected under the pressure of steam and for reversing said valves by the opposite tilting of said receptacle when relieved from weight of the water, whereby the steam atmosphere will be condensed by the sprinkler and a vacuum will be placed on the steam system.

4. In an automatic trap, a rockable receptacle having a check controlled inlet for water of condensation and a check controlled outlet.

trolled outlet, a water sprinkler in the upper portion of said receptacle, a valve controlled water supply conduit, a flexible connection between said water supply conduit and said sprinkler, a valve controlled steam inlet to the upper portion of said receptacle, a weighted lever operated by the accumulation of water within said receptacle, a seat formed in one end of said lever, a link, one end of which is adapted to be received by the seat and having its remaining end connected with the valve operating mechanism.

5. In an automatic trap, the combination of a rockable receptacle having trunnion supports, of check controlled inlet and outlet conduits communicating with said receptacle through one of said trunnion supports, a steam inlet to said receptacle through another of said trunnion supports, a valve con-

trolling said steam inlet, a sprinkler in said receptacle, a water supply conduit, a flexible connection between said water supply conduit and sprinkler, permitting the tilting of said receptacle, a valve controlling the admission of water to said sprinkler, a weighted lever actuated by the accumulation of water within said receptacle, a link having connection with said weighted lever, and said link being adapted to operate the valve operating mechanism. 20

25 In testimony whereof we affix our signatures in presence of two witnesses.
